(57) **CLAIM**

The ornamental design for a dose cup, substantially as shown and described.

DESCRIPTION

FIG. 1 is a perspective view of a dose cup with a container shown in dotted lines for environmental purposes only;

FIG. 2 is a top plan view of the dose cup;

FIG. 3 is a side view thereof (all sides being the same); and, FIG. 4 is a bottom plan view thereof.

The broken lines in the drawings depict environmental structure, which forms no part of the claimed design.
